UNITED STATES PATENT OFFICE.

MAURICE S. ROSENFIELD, OF NEW YORK, N. Y., ASSIGNOR TO DECALMO MACHINE CO., INC., A CORPORATION OF DELAWARE.

DECALCOMANIA-TRANSFERRING MACHINE.

1,831,580.

Specification of Letters Patent.

Patented Feb. 24, 1920.

Application filed August 10, 1918. Serial No. 249,315.

To all whom it may concern:

Be it known that I, MAURICE S. ROSENFIELD, a citizen of the United States, residing in the borough of the Bronx, in the 5 county of Bronx, in the city and State of New York, have invented a certain new and useful Improvement in Decalcomania-Transferring Machines, of which the following is a specification.

10 The present invention relates to an improvement in decalcomania transferring machines.

It has been proposed heretofore to construct a decalcomania transferring machine 15 employing a conveyer or endless belt upon which the article or articles to be stamped all occupy the same plane and are presented in that plane in succession to the action of the heated presser iron and the transfer 20 tape upon which the decalcomanias are temporarily impressed, in order to effect a transfer of the decalcomanias from the tape to the articles. In such machines, the transfer tape usually occupies a definite plane 25 and the presser iron has a certain, definite range of action. Such machines are, accordingly, not adapted for operation on articles which are arranged or stacked one upon another in piles. And it has not been 30 heretofore proposed, so far as is known, to construct a decalcomania transferring machine adapted for operation on articles arranged in stacks or piles, where the continuity of the pile is not permitted to be 35 broken. The machine of the present invention is particularly adapted for transferring decalcomanias to articles arranged in piles, although it may be equally successively employed on articles all occupying the same 40 plane.

Where the articles are arranged in piles, as each article is stamped or receives a decalcomania, it is folded back in order to expose the next underlying article to the 45 action of the transfer tape and the heated presser iron. Upon the completion of the transferring operation upon the pile of articles, they are folded back to their original position, and so the continuity of the pile 50 is not disturbed. The pile of articles to be stamped rests upon a work support and as each article is stamped and folded back to expose the next underlying article, the presser iron descends progressively lower 55 toward the work support. It is thus seen

that each article is acted upon in a different plane of operation. A proper transference of the decalcomania from the transfer tape to the article requires not only that the presser iron be at a certain temperature, but 60 also that it be in engagement with the transfer tape and the article for a predetermined and requisite length of time under the requisite amount of pressure. The application of the proper amount of heat for the 65 required time under a certain amount of pressure effects a proper transference of the decalcomania. If the heated presser iron is in engagement with the transfer tape and the article for either too long a time 70 or not long enough, a successful transference of the decalcomania is not effected; in the first instance, because the composition of the decalcomania is crystallized and, in the second instance, because the decalcomania is 75 not properly loosened from the transfer tape.

One feature of the present invention is to provide a decalcomania transferring machine with mechanism of such construction 80 that the presser iron will be in operation, that is to say, in engagement with the transfer tape, pressing it against the article to be stamped, for a predetermined length of time, regardless of the position the article 85 occupies in the pile. In other words, whatever the distance from the table the presser iron occupies in performing its transferring operation, it remains in each operative position an equal and predetermined length of 90 time. This mechanism also assures that the presser iron will exert an equal pressing force upon each article, irrespective of its position in the pile. As a result of this action of the presser iron, the operation 95 of removing the decalcomanias from the transfer tape and causing them to adhere to the articles is effectively performed.

Inasmuch as the presser iron traverses varying distances in order to press the transfer tape against the articles to be stamped, it will be recognized that the transfer tape must normally be at such distance from the work support as not to interfere with a fresh supply of articles placed on the work support, and yet must be so supported as to be movable into close proximity with the work support. Another feature of the invention is the provision of means for supporting the transfer tape in order that it may occupy 105 110

various positions of operation. The transfer tape is supported in such manner that it passes in close proximity to the heated presser iron. If, as above pointed out, the 5 decalcomanias remain too long in the presence of heat, they become crystallized; accordingly, it is another feature of the invention to feed the transfer tape so that the portions thereof upon which the decalcomanias are impressed come into position to be acted upon only as the presser iron moves into its operative position. Other 10 features of the invention will appear as the description of the machine embodying the invention proceeds. The invention consists 15 in the improved decalcomania transferring machine hereinafter described and particularly pointed out in the appended claims.

The preferred form in which it is at present contemplated embodying the invention is illustrated in the accompanying drawings, in which Figure 1 is a side elevation of the improved decalcomania transferring machine; Fig. 2 is a vertical section of the 25 machine shown in Fig. 1, with the parts in their normal or inoperative positions; Fig. 3 is a section similar to Fig. 2, with the parts occupying their operative or transferring positions; Fig. 4 is a view similar to the 30 upper part of Fig. 2, but on an enlarged scale, this view being also a section taken on the line 4—4 of Fig. 5, looking in the direction of the arrow; Fig. 5 is a plan view of the upper part of the machine; Fig. 6 35 is a section taken on the line 6—6 of Fig. 4; Fig. 7 is a front elevation of the upper part of the machine; Fig. 8 is a sectional view taken on the line 8—8 of Fig. 4; Fig. 9 is a sectional view taken on the line 9—9 40 of Fig. 4; Fig. 10 is a sectional view taken on the line 10—10 of Fig. 7; Fig. 11 is a sectional view taken on the line 11—11 of Fig. 12 and shows the construction of the 45 presser iron actuating parts at the bottom of the machine; Fig. 12 is a sectional plan of the parts shown in Fig. 11; and Figs. 13 and 14 are sections taken on the lines 13—13 and 14—14, respectively, of Fig. 11.

The pile or stack of goods, commonly 50 fabrics or articles of apparel, to which the decalcomanias are to be applied rest upon a work support or work supporting table 87, in position to be subjected to the action of a heated presser iron 64, which acts to heat 55 and press a decalcomania-carrying web or tape 56, known as the transfer tape, against the articles for a predetermined length of time under a predetermined amount of pressure. The presser 64 is supported in a 60 presser carrying head 65 projecting forwardly from a slide 39 mounted for reciprocating movements in vertical guide-ways 40 formed in the upper part 3 of the frame 1 of the machine. The presser is heated in 65 the usual way by electricity conducted

through a wire 86. The presser 64 is provided with a shank 75, which is received in an opening in the upper part 72 of the head 65. Check-nuts screwed on to the presser shank limit the downward movement of the 70 presser relatively to the head 65. A spring 74 surrounding the shank of the presser tends to force it downwardly against the transfer tape 56. The presser is lifted against the action of the spring 74, in order 75 to normally hold the presser away from the tape by means of a lever 76 pivoted at 77 in ears 78 carried by the head 65. The forward end of the lever 76 is received in a recess fashioned in the shank of the presser, 80 and the rear end of the lever is bifurcated, as shown in Fig. 9, so as to accommodate between the legs of the lever a pawl 79, pivoted to the lever at 80. Springs 82, connected at their rear ends to pins carried by the lever 76 and at their forward ends to a pin 81, carried by the pawl, tend 85 to press the upper hook-shaped end of the pawl forward into engagement with a lug 73 formed on the upper part 72 of the head 90 65. The lever 76 is actuated to raise the presser 64 against the action of the spring 74, when by the upward movement of the slide 39 the upper edges 83 of the rear end of the lever 76 and the horizontal arm of the 95 pawl 79 are brought into engagement with the lower end of a stop pin 84, adjustably secured in a bracket 85 fastened to the upper part 3 of the frame of the machine, as shown in Fig. 2. This is the normal or inoperative 100 position of the presser and its associated parts, the presser 64 and its head 65 always rising to this position after having been forced down against the articles in order to impress a decalcomania thereon. 105 As the head 65 descends toward the work support 87, the lever 76 and pawl 79 become disengaged from the stop pin 84; thereupon the spring 74 is free to force the presser 64 downwardly below the bottom of 110 the presser carrying head and against the transfer tape 56, as shown in Fig. 3; and the springs 82 are free to move the hook-shaped end of the pawl 79 into engagement 115 with the lug 73, so as to lock the presser 64 in its lowered position in fixed relation with the head 65. This enables the presser to be forced firmly against the articles during the transferring operation.

The slide 39 is moved downwardly to 120 bring the presser 64 into operative engagement with the transfer tape 56 and the pile of articles on the work support by means of a rod 25 connected at its upper end with the slide and at its lower end with an eccentric 125 24, loosely mounted on a shaft 13 journaled in bearings 14 and 15 rising from a bracket 10 fixed on the lower part 2 of the frame of the machine. A turnbuckle 38 affords provision for adjusting the rise and fall of the 130

slide and the presser carrying head. The cam 24 carries a segmental gear 23, which is arranged to be engaged and driven by a pinion 18 having a conical central opening 5 therein adapted to engage a truncated cone 17 formed on the outer end of an arm 16 fastened to the shaft 13. The pinion 18 is held in position on the cone 17 by means of a pin 20, the large end 19 of which is received in an annular recess of the pinion. A recess is formed in the outer end of the arm 16 to accommodate a spring 22, the outer end of which presses against a nut 21 received on the end of the pin 20. By turning the nut 21 the tension of the spring 22 may be regulated so as to cause the pinion 18 to turn upon the cone 17 with difficulty.

When the machine is started in operation, a counter-clockwise movement is imparted to 20 the shaft 13 and arm 16 so as to bring the pinion 18 into engagement with the adjacent end of the segment 23. The friction of the pinion 18 upon the cone 17 is such that the pinion by its engagement with the segment 25 23 turns the cam 24, so as to impart a downward movement to the rod 25, thereby moving the head 65 and the presser toward the work support 87. When the presser comes into engagement with the pile of articles on the work support and it is arrested thereby, the pinion 18 is then caused by the constant turning movement exerted upon the arm 16 by the shaft 13 to turn on the cone 17 and so travel over the teeth of the segment 23 until it reaches the other end thereof; whereupon, the segment being released from the pinion, the head 65 is returned to its raised or inoperative position.

The length of time required for the proper 40 softening of the sizing by which the decalcomania is held on the tape so that the decalcomania may become loosened from the tape and be impressed upon the article is determined by the length of the segment 23. 45 Where a shorter time is required, the segment will be correspondingly shortened; and where a longer interval of time is necessary, the segment will be correspondingly lengthened. It is obvious the same results

50 can be obtained by regulating the speed of the shaft 13. The force with which the presser is pressed against the articles is determined by the tension which the spring 22 exerts in holding the pinion 18 against the cone 17. It will thus be recognized from the above description that whatever the operative position of the presser, whether relatively near to or far from the work support, the presser will act to press the transfer tape against each article for an equal and predetermined length of time under a constant and predetermined pressure, and so effect, when properly heated, a successful transference of the decalcomanias from 55 the tape to the articles.

The slide 39 is moved upwardly to return the presser into its normal or inoperative position by means of the spring 45, surrounding a rod 42, the upper end of which is adjustably secured to a bracket 41 integral with the slide 39. The upper end of the spring 45 engages a disk 44 fastened upon the rod 42, and the lower end of the spring engages the corresponding disk 46 which rests upon the upper end of a guide 47, in which the lower end of the rod 42 slides. The upper end of the rod slides in a guide 48. The tension of the spring 45 may be regulated by adjusting the nuts 43. In order that the head 65 and the parts carried by it may be returned to their raised position without shock or jar to the machine, a dash pot 52 is provided in which a piston or plunger 51 slides, the rod 50 of which is pivotally connected at its upper end to a bracket 49 projecting rearwardly from the slide 39.

The shaft 13 is driven by means of a clutch disk 28 fixed to the shaft, when a locking pin 27 mounted in the clutch is turned to such position as to register and lock with a bushing 26 carried by a worm-gear 12 loosely mounted upon the shaft 13. The locking pin 27 is held from end-wise movement by means of a set-screw 29. The outer end of the locking pin 27 is provided with a finger 30 which is yieldingly pressed toward the shaft 13 by a spring 31. The lower or free end of the finger 30 is normally in engagement with a shoulder 32 formed on 100 a dog 33 pivoted at 34 in the frame of the machine. When the finger 30 is in engagement with the shoulder 32 of the dog 33, the pin 27 is out of locking engagement with the bushing 26 so that the worm gear 12 105 cannot drive the clutch 28. The free outer end of the dog 33 is connected with a treadle 36 by a link 35. A spring 37 surrounding the link tends to raise the treadle 36 and the dog 33 so as to hold the shoulder 32 on the 110 dog in the path of movement of the finger 30. A stop pin 38 limits the upward movement of the dog.

The worm gear 12 is constantly driven by a worm 11, fixed upon the main shaft 8 of 115 the machine, which is journaled in a long bearing 9 supported on the bracket 10. The shaft 8 is provided with a clutch member 7 driven by a co-operating clutch member 6 secured on the outer end of the shaft 5 of the 120 motor 4, which constitutes the source of power of the machine. The machine is started in operation by the workman forcing the treadle down so as to disengage the dog 33 from the finger 30. Thereupon the spring 31 acts to turn the locking pin 27 so as to lock the clutch 28 against the worm gear 12. The shaft 13 is then turned by the shaft 8.

Inasmuch as the present construction of decalcomania transferring machine is 130

adapted to accommodate a stack or pile of articles of considerable thickness, which diminishes as the succeeding top layers of the articles are operated upon, so that when the 5 last article resting on the work support is reached, the presser must descend into close proximity with the table; it is necessary, therefore, that the transfer tape be normally held in such position as to permit 10 the stack or pile of articles to be interposed between it and the work support, and it is also necessary that the transfer tape be so supported that it may be moved into engagement with each article, regardless of its position in the pile. After a decalcomania is transferred from the transfer tape to an article, it is necessary to present a fresh decalcomania to the action of the presser. The means for supporting the transfer tape and 15 20 the means for feeding it will be conjointly described. The roll of transfer tape is carried by a reel 57 fulcrumed on a stud 58, fixed in brackets 59 extending rearwardly from the machine. From the reel 57 the 25 transfer tape passes under a roll 53 over a roll 54 and under another roll 55. The rolls 53 and 54 are journaled in the outer end of the bracket 49, and the roll 55 is supported in bearing blocks which slide loosely in slots 30 formed in the upper part of the outer end of the bracket 49 so that the roll 55 may press against the transfer tape under the action of gravity. From the rolls 54 and 55 the tape passes through an aperture 62, 35 formed in the slide 39, and under a leaf spring 63 secured to the bottom of the presser carrying head 65, and thence over the lower open side of the head 65 up through a slot formed by a guide-way 66, 40 secured to the front of the head and thence over a rail 67 to the feed rolls 68 and 69. From the feed rolls the tape passes through a chute 61, supported by the upper part of the machine and by the upper part 60 of the 45 bracket 59. The above described construction is such that the part of the transfer tape to be acted upon by the presser is carried toward and from the table with the head 65; and, accordingly, the tape never interferes with placing work in the machine, having regard to the capacity of the machine, whatever the thickness of the pile of 50 articles.

Inasmuch as a portion of the transfer tape 55 56 is carried in close proximity to the under surface of the heated presser iron 64, crystallization of the sizing by which the decalcomania is held on the transfer tape and crystallization of the other constituents of 60 the decalcomania is prevented by feeding the transfer tape forward when the presser is descending into operative position, so that the length of time the presser is in engagement with the transfer tape will be just sufficient to melt the sizing, and also the adhe-

sive which serves to fasten the decalcomania upon the article receiving it. The successive lengths of transfer tape carrying the decalcomanias are successively brought under the presser 64 as the presser descends 70 into operative position by holding the feed roll 68 stationary during the first part of the descent of the presser carrying head 65, so that the pull of the head 65 against the tape will serve to draw the requisite length 75 of tape from the reel 57, thereby correctly positioning a decalcomania under the presser 64. Thereafter, during the remainder of the descent of the head 65 toward the work support 87 the transfer tape is fed back- 80 wardly from the feed rolls 68 and 69.

The lower feed roll 68 is provided with a bushing 94 (Fig. 8), which is loosely mounted on a shaft 95, journaled in the upper end 96 of the frame of the machine. One 85 end of the roll is recessed to accommodate a spring clutch 99 loosely but snugly engaging the shaft 95, the outer end of the spring 99 being received in a hole in the roll. This construction is such that when the shaft 95 90 is driven in one direction, it tends to unwind the spring and, therefore, no turning movement is imparted to the roll 68; but when the shaft is turned in the opposite direction, it tends to wind up the spring, (which fits 95 so closely over the shaft 95 that there is practically no lost motion) and so the turning of the shaft 95 imparts a turning movement to the roll 68. The opposite end of the roll 68 is recessed to receive the hub of 100 a ratchet wheel 98, which is fixed to the roll 68, but is loosely supported on the shaft 95. Alongside the ratchet wheel 98 a cam 97 is rigidly secured to the shaft 95. The cam 97 is adapted to be brought into engagement 105 with the curved part 105 of a pawl 103 pivoted at 102 on the frame of the machine. The pawl 103 is provided with a shoulder 104 arranged to be engaged by the teeth of the ratchet wheel 98. A spring 106, one end 110 of which is fastened to the free end of pawl 103 and the other end of which is fastened to a pin 107, tends to move the shoulder 104 into the path of movement of the teeth of the ratchet wheel. These parts are constructed and arranged in such manner that during the first part of the downward movement of the presser carrying head 65, the shoulder 104 is engaged by one of the teeth 115 of the ratchet wheel, thereby preventing the 120 turning movement of the feed roll 68; but when the requisite length of tape has been drawn from the supply roll, so as to position a fresh decalcomania under the presser 64, then the cam 97 is brought into engagement 125 with the pawl 103 to release the shoulder 104 from the ratchet wheel 98, so as to permit the feed roll 68 to turn backwardly, thereby permitting the used tape to be drawn down from the feed rolls as the head 130

65 is progressively lowered toward the work support 87 as the successive articles are operated upon and either removed or folded back in the pile.

5 Turning movements in a direction to feed the tape forward are imparted to the feed roll 68 by a pinion 101 fastened to the shaft 95. The pinion 101 meshes with a rack 108 secured to the front of the head 65, as shown 10 in Fig. 7. The upper end of the rack 108 is inclosed in a guard 109. During the first part of the downward movement of the head 65, while the appropriate length of tape is being drawn from the source of supply, and 15 while the shoulder 104 is in engagement with the ratchet wheel 98, the turning movement of the pinion 101 and the shaft 95 imparted by the descending rack is not communicated to the feed roll 68, because the 20 turning of the shaft 95 in this direction tends to unwind the spring clutch 99. When the shoulder 104 of the pawl 103 is disengaged from the ratchet wheel 98, the roll 68 is turned in a reverse or backward direction 25 (to permit a backward movement of the tape), not through its shaft 95, but by the pulling action exerted upon it by the descending head 65; and in this connection it will be noted that the roll 68 is provided at 30 its outer ends with pins 70 for engagement with perforations along the edges of the transfer tape. When the head 65 rises, the movement imparted to the pinion 101 and the shaft 95 by the rack 108 is imparted to the roll 68 by the spring clutch 99. While 35 the head 65 is rising, the turning movement thereby imparted to the roll 68 serves to take up the slack in the tape caused by the rising of the head.

40 It is to be observed that the length of transfer tape advanced during each cycle of operation into position under the presser 64 bears a definite relation to the even divisions of the circumference of the feed roll 68. 45 The number of teeth on the ratchet wheel 98 equals the number of feed lengths of transfer tape necessary to equal the circumference of the feed roll. On each feed length of tape one decalcomania is impressed. By 50 means of this construction a definite and positive amount of tape is advanced during each feeding operation. The cam 97 is so positioned with respect to the teeth on the ratchet wheel that it does not come into engagement with the pawl 103 to release the shoulder 104 from the ratchet wheel until the requisite amount of transfer tape has been drawn from the source of supply. The ratchet wheel being held fast while the head 55 65 is descending a sufficient distance to draw the requisite amount of tape from the source of supply, and then released to turn backward with the feed roll 68 when the head 65 rises again and a forward movement is 60 imparted to the feed roll and the ratchet

wheel, the next succeeding tooth of the ratchet wheel will be presented to the shoulder 104, and so the feed roll and the ratchet wheel will be advanced an amount corresponding to the divisions of the ratchet 70 wheel. The divisions on the ratchet wheel are thus seen to correspond to the number of lengths of tape necessary to equal the circumference of the feed roll. In the present instance, the ratchet wheel 98 has three 75 teeth, and so three lengths of transfer tape are necessary to equal the circumference of the feed roll 68. Each section of the tape carrying a decalcomania is called a length of tape. 80

The upper feed roll 69 is secured to a shaft 88 journaled in the bifurcated forward end of a frame 90 pivoted in ears 92 rising from the upper part of the frame of the machine. Spring-pressed plungers 921 (Fig. 4) engaging with the frame 90 serve to press the roll 69 lightly against the transfer tape. Stop pins 93 adjustably secured in the frame 90 determine the amount of downward movement of the roll 69. Grooves 71 formed in 90 the roll 69 accommodate the drive pins 70 of the roll 68.

The various steps in the operation of the improved decalcomania transferring machine will be briefly recapitulated. With the 95 parts in their normal position, as shown in Figs. 1 and 2, and the presser carrying head 65 and its associated parts in raised position, so as to permit the stack or pile of articles to be stamped to be placed on the work support, the workman places the work in proper position on the support and presses the treadle 36. This act disengages the dog 33 from the finger 30, permitting the spring 31 to turn the locking pin into such position 100 that it will register with and be received in the bushing 26 so as to lock the clutch 28 to the constantly driven worm gear 12. Thereupon the rotation of the shaft 13 will carry the crank arm 16 and its pinion 18 into engagement with the segmental gear 23. The friction of the pinion 18 upon the cone 17 is such as to permit the pinion to turn the segment 23 and the parts connected with it. The turning of the eccentric 24 results in the 105 downward movement of the slide 39 and the presser carrying head 65. As the head 65 descends, the lever 76 and pawl 79 are released from the stop pin 84, so as to permit the spring 74 to force the heated presser iron 110 64 below the bottom of the head 65 and into engagement with the transfer tape 56. The spring 82 is also released to force the latch 79 into engagement with the lug 73 so as to lock the presser in fixed relation with the 115 head 65. During the first part of the downward movement of the presser carrying head the feed roll 68 is held locked by the engagement of the shoulder 104 on the pawl 103 with one of the teeth of the ratchet wheel 98. 120 125 130

When by the descent of the presser carrying head the requisite amount of transfer tape has been drawn from the reel 57 so as to properly position a fresh decalcomania 5 under the presser, the cam 97 swings the pawl 93 outwardly to release the shoulder 104 from the ratchet wheel. The feed roll 68 is now free to turn in a reverse direction so that as the head 65 continues to descend 10 toward the work support, it may pull the used tape with it and not disturb the position of the decalcomania in engagement with the presser. As the head continues to descend, the presser iron forces the tape against 15 the topmost article of the pile on the work support. When the resistance becomes sufficiently great to overbalance the friction of the pinion 18 upon the cone 17, the pinion turns and rides over the teeth of the segment 20 23. The length of time required for the passage of the pinion over the segment 23 determines the length of time the presser shall be in engagement with the tape and the pile of work. This length of time is sufficient 25 to effect a proper transference of the decalcomania from the tape to the article. When the pinion 18 disengages itself from the segment 23 the spring 45 acts to raise the slide 39 and the parts connected with it, 30 thereby restoring the parts to their normal position. The dash pot 52 causes the slide and its connected parts to rise into their normal or inoperative position without shock. As the head 65 rises, the rack 108 35 turns the feed roll 68 in a forward direction to take up the slack in the transfer tape. The workman now removes or folds back the article stamped and again presses on the treadle 36 so as to cause the presser to again 40 come into operative position. If desired, the treadle may be permanently held down and then the parts will automatically perform their cycle of operation, the workman removing or folding back each article as it is 45 stamped. As the successive articles are stamped and removed or folded back, so that the presser descends progressively lower toward the work support to perform the next succeeding operation, the friction of the 50 pinion 18 on the cone 17 and the length of the segment 23 assure that the presser will exert an equal force upon each article and will be in contact with each article an equal and predetermined length of time. 55 The machine has been described as being particularly adapted for operation upon a stack or pile of articles, the thickness of which progressively diminishes as the succeeding articles are stamped. It will be 60 recognized, however, that the machine of the invention is not to be limited in its application to operation on stacks or piles of articles, inasmuch as it may equally well be employed upon a succession of articles all 65 occupying the same plane, requiring the

presser to be moved into a certain definite position during each cycle of operation.

Having thus described the invention, what is claimed is:—

1. A decalcomania transferring machine 70 having, in combination, a fixed work support, a transfer tape supporting and feeding means, a presser supported to have operative positions at different distances from the work support, and means for actuating 75 the presser so that it will remain in each position of operation an equal and predetermined length of time.

2. A decalcomania transferring machine 80 having, in combination, a fixed work support, means for feeding a transfer tape, a presser supported to have operative positions at different distances from the work support, and means for actuating the presser so that it will exert an equal pressure in 85 each position of operation.

3. A decalcomania transferring machine having, in combination, a fixed work support, means for feeding a transfer tape, a presser supported to have operative positions at different distances from the work support, and means for actuating the presser 90 so that it will exert an equal pressure in each position of operation and will also remain in each position of operation an equal 95 and predetermined length of time.

4. A decalcomania transferring machine having, in combination, a fixed work support, means for feeding a transfer tape, a presser supported to have positions of operation 100 at different distances from the work support, and actuating means for the presser constructed and arranged to exert an equal force on the presser in each of its positions of operation. 105

5. A decalcomania transferring machine having, in combination, a fixed work support, means for feeding a transfer tape, a presser supported to have positions of operation at different distances from the 110 work support, and means for actuating the presser constructed and arranged so that the force with which the presser is actuated and the length of time it is under actuation are equal for each and all the positions of operation. 115

6. A decalcomania transferring machine having, in combination, a work support, means for feeding a transfer tape, a presser supported to have positions of operation 120 at different distances from the work support, and means for actuating the presser so that it will exert equal pressure for equal and predetermined lengths of time in each position of operation, comprising a segmental gear connected with the presser, and a frictionally held pinion for driving the segmental gear. 125

7. A decalcomania transferring machine having, in combination, a work support, 130

means for feeding a transfer tape, a presser, and means for actuating the presser comprising a segmental gear connected with the presser, a frictionally held pinion for driving the segmental gear, and means for imparting a swinging movement to the pinion.

8. A decalcomania transferring machine having, in combination, a work support, means for feeding a transfer tape, a presser, and means for actuating the presser including a segmental gear and a pinion, the length of time the presser is in operative position being determined by the length of the segment, and the pressure exerted by the presser being determined by the friction of the pinion on its bearing.

9. A decalcomania transferring machine having, in combination, a work support, means for feeding a transfer tape, a presser, and means for actuating the presser comprising a shaft having a crank arm, a frictionally held pinion on the arm, a segmental gear connected with the presser and arranged to be engaged by the pinion, and means for driving the shaft.

10. A decalcomania transferring machine having, in combination, a work support, means for feeding a transfer tape, a presser, and means for actuating the presser comprising a segmental gear connected with the presser, a pinion mounted to have a swinging movement and arranged to engage and drive the segmental gear to move the presser into operative position, the pinion being frictionally mounted so that when the presser is in operative position the pinion rides over and becomes disengaged from the segmental gear, and means for swinging the pinion.

11. A decalcomania transferring machine having, in combination, a work support, a presser carrying head, means for moving the head toward and from the work support, a presser movably mounted on the head, means connected with the head for supporting the part of the transfer tape to be acted on in position to be engaged by the presser, means for normally holding the presser out of engagement with the tape and means for moving the presser into engagement with the tape before the presser reaches its operative position.

12. A decalcomania transferring machine having, in combination, a work support, a presser carrying head, a presser movably supported in the head, means for supporting the transfer tape against the head, means for normally holding the presser out of engagement with the tape and means for moving the presser into engagement with the tape and locking the presser on the head.

13. A decalcomania transferring machine having, in combination, a fixed work support, a presser supported to have operative positions at different distances from the

work support, means for actuating the presser, and means for holding the transfer tape against the presser in the different operative positions of the latter.

14. A decalcomania transferring machine having, in combination, a fixed work support, a presser supported to have operative positions at different distances from the work support, means for actuating the presser and means for holding the transfer tape in position to be operated upon by the presser whatever the operative position of the latter, said means carrying the transfer tape toward and from the work support with the presser.

15. A decalcomania transferring machine having, in combination, a work support, a reciprocatory presser carrying head, a presser movably mounted on the head and normally out of engagement with the transfer tape, means for feeding the tape, and means for locking the presser to the head and in engagement with the tape.

16. A decalcomania transferring machine having in combination, a work support, a reciprocatory presser carrying head having an open ended recess, means for feeding the transfer tape across the open end of the recess a presser mounted in the recess and normally held out of engagement with the transfer tape, means for moving the presser into engagement with the tape as the head carries the presser into operative position, and means for reciprocating the head.

17. A decalcomania transferring machine having, in combination, a work support, a presser supported to have operative positions at different distances from the work support, means for supporting a transfer tape between the presser and the work support, and means for feeding the transfer tape to present a fresh portion thereof to the action of the presser as the latter moves toward the work support.

18. A decalcomania transferring machine having, in combination, a work support, a presser supported to have operative positions at different distances from the work support, means for feeding the transfer tape to present a fresh portion thereof to the action of the presser while the presser travels through a definite distance in moving toward its operative positions, and means for actuating the presser.

19. A decalcomania transferring machine having, in combination, a work support, a presser supported to have operative positions at different distances from the work support, means for feeding the transfer tape to present a fresh portion thereof to the action of the presser while the presser travels through a definite distance in moving toward its operative positions, means for holding the used part of the tape during the feed and means for releasing the used part

of the tape after the feed so that it may follow the presser as the latter moves into its operative positions.

20. A decalcomania transferring machine having, in combination, a work support, a presser, means for moving the presser toward the work support into operative position, means for feeding the transfer tape to present a fresh portion thereof to the action of the presser while the presser travels through a definite portion of the distance it travels in moving into operative position, and means for feeding backward the used part of the tape to accommodate the presser as it moves the remainder of the distance into operative position.

21. A decalcomania transferring machine having, in combination, a work support, a presser, means for moving the presser toward the work support, means for supporting a roll of transfer tape, a feed roll, means for holding the feed roll fast during the first part of the movement of the presser toward the work support so as to enable the presser to draw from the roll of tape a length equal to an even division of the circumference of the feed roll, and means for turning the feed roll in a direction to take up the amount of tape fed forward.

22. A decalcomania transferring machine having, in combination, a work support, a presser supported to have operative positions at various distances from the work support, means for supporting a roll of transfer tape, a feed roll, means for feeding the tape to present a fresh portion thereof to the action of the presser as the latter descends part way into operative position, means for causing the length of tape fed forward to be equal to an even division of the circumference of the feed roll, means for holding the feed roll stationary during the feeding of the tape and for releasing the feed roll to permit it to let back used tape as the presser moves the rest of the way into operative position, and means for turning the feed roll in the opposite direction to take up the slack tape as the presser moves out of operative position.

23. A decalcomania transferring machine having, in combination, a work support, a presser, means for actuating the presser, means including a feed roll for feeding the transfer tape to present a fresh portion thereof to the presser during the first part of the movement of the latter into operative position, and a ratchet wheel connected with the feed roll, the length of tape fed for-

ward at each feeding operation being equal to an even division of the circumference of the feed roll and the division of the feed roll corresponding to the number of teeth on the ratchet wheel.

24. A decalcomania transferring machine having, in combination, a work support, a presser, means for actuating the presser, and a transfer tape feeding means comprising a feed roll, a ratchet and pawl connected therewith, a shaft upon which the feed roll is loosely mounted, connections between the feed roll and its shaft for positively driving the feed roll and only in one direction, and means connected with the presser for actuating the feed roll shaft.

25. A decalcomania transferring machine having, in combination, a work support, a presser supported to have operative positions at different distances from the work support, means for actuating the presser, means connected with the presser for feeding forward the transfer tape to present a fresh portion thereof to the action of the presser as the latter moves through a definite distance toward its operative positions, and means for letting back the used tape as the presser completes its movement into operative position.

26. A decalcomania transferring machine having, in combination, a fixed work support, a presser supported to have operative positions at different distances from the work support, means for actuating the presser so that it will remain in each operative position an equal and predetermined length of time, and means for feeding forward the transfer tape so as to present a fresh portion thereof to the action of the presser as the latter moves into operative position.

27. A decalcomania transferring machine having, in combination, a work support, a presser supported to have operative positions at different distances from the work support, means for actuating the presser so that it will remain in each operative position an equal and predetermined length of time, and a transfer tape feeding means comprising means for feeding forward the tape while the presser is moving through a definite distance to its operative positions, and means operating thereafter to cause the used tape to be fed backward as the presser moves the remainder of the distance into its operative positions.

MAURICE S. ROSENFELD.
